ISAAC H. FARMER, OF MONTEZUMA, IOWA.

REVERSIBLE DISK-SHARPENING TONGS.

Application filed May 10, 1926. Serial No. 107,948.

The object of this invention is to provide an improved construction for tongs employed in sharpening the disks of disk harrows, roller cutters and the like.

5 A further object of the invention is to provide an improved disk-sharpening tongs in which the blade is loosely mounted in a seat, is instantly removable by upward movement in order to reverse its position, and 10 is quickly adjusted as to elevation by means of a set screw engaging its lower end.

15 A further object of the invention is to provide an improved disk-sharpening tongs in which the blade and roller are carried by the respective arms and are reversible as to position so as to sharpen both sides of a disk conveniently.

20 A further object of the invention is to provide an improved disk-sharpening tongs wherein one arm of the tongs has a quick-detachable connection to the other whereby it may be instantly removed and reversed without the aid of any tool.

25 With these and other objects in view, my invention consists in the construction, arrangement and combination of elements hereinafter set forth, pointed out in the claims and illustrated by the accompanying drawing, in which—

30 Figure 1 is a perspective view of my improved tongs.

Figure 2 is a plan view illustrating the tongs in position for sharpening one side of the edge of a disk.

35 Figure 3 is a plan view illustrating the tongs in reversed position for sharpening the other side of the cutting edge.

40 Figure 4 is a vertical section on the line 4—4 of Figure 3, showing particularly the means for mounting and adjusting the cutting blade.

45 In the construction of the device as shown the numeral 10 designates a standard which has integrally formed at its lower end a suitable base 11 and at its upper end a pivot stud 12. Pivotedly mounted on the stud 12 is the blade-carrying arm 13 of the tongs, with which cooperates a roller-carrying arm 14 which is pivotally and also removably mounted on said stud. These parts 50 may be made of any suitable material such as mild steel or malleable iron and of any convenient size and shape. The arms 13 and 14 are arranged to swing in substantially horizontal planes and are pivoted nearer one end than the other the longer portions

of the tong arms or levers serving as handles by which they may be manipulated. Formed on the short end of the arm 13 is a yoke-shaped bracket 15 arranged at an obtuse angle to the arm and having in its upper portion a rectangular hole or seat in which a cutting blade 16 is removably and adjustably mounted. The blade 16 fits snugly in its seat and is vertically movable therein, 60 and it has at its upper end an angularly arranged portion 17 having a cutting edge. In the lower portion of the bracket 15 is threaded an adjusting screw 18 which engages the lower end of the blade 16 and serves to 65 adjust the said blade vertically as said screw is moved up or down in its seat. On the short end of the tong arm 14 is rotatably mounted a roller 19 which is opposed to the cutting blade 16. The short end of 70 the arm 14 is bent or curved toward the other arm 13 and bracket 15 so that the edge of the roller 19 may be brought into a position substantially parallel with the cutting edge of the blade when the tong arms 75 are moved toward each other manually, as will be clearly seen in Figures 2 and 3. This permits the peripheral portion of a disk such as 20 to be received between the short arms of the tong arms, and be pressed 80 by the roller 19 against the cutting edge of the blade 16 and be sharpened thereby. The roller 19 preferably is beveled or tapered at its outer end so as to fit against the convex side of a disk as shown in Figure 3. 85

90 In practical use the disk gangs are mounted on any suitable type of machine commonly provided for that purpose and are rotated by power to cause the disks to revolve, and the tongs are so placed as to engage the peripheral portions of the disks successively until the desired grinding operation is completed. In the common type of disk harrow the disks on opposite sides of the center are oppositely arranged, and therefore it is desirable to make the tongs reversible as I have shown them in order that the oppositely arranged disks may be ground from the same side of the machine and in the same manner. This reversing function is also desirable where it is desired to grind the disks on both sides of their peripheries, as is shown in Figures 2 and 3. To facilitate this reversal I have provided 95 the stud 12 with an elongated head designated by the numeral 21, said head being 100 arranged transversely of the arm 13. The 105 110

tong arm 14 is provided with an elongated slot 22 extending lengthwise and so arranged that it may be removed or replaced relative to the head 21 of the stud when the arm 14 is extended to a position where it is substantially at right angles to the arm 13. When in its normal operating position, the arm 14 is held by the head of the stud in a pivotal engagement relative to the other arm 13. This permits the arm 14 to be quickly and readily removed and reversed, by turning it over, without the use of a tool of any kind. The blade 16 is also reversed at the same time, so that it points toward the roller 19, and the device may be used effectively in either position.

I claim as my invention—

1. A disk-sharpening tongs, comprising a support, a blade-carrying arm pivoted thereon, a blade reversibly and adjustably mounted in said arm, a pivot stud having an elongated head, a second arm formed with a longitudinal slot arranged to be removed and replaced relative to said headed stud when in a certain position, and a roller pivoted on the second arm in opposition to said blade.

2. In a disk-sharpening tongs, a support, an arm pivoted thereon and formed at one end with a bracket having a vertical seat, 30 a cutting blade fitted to said seat and removable by upward movement therefrom, and an adjusting screw vertically threaded in the lower part of said bracket and engaging beneath the lower end of said blade, 35 whereby the vertical adjustment of said blade may be effected.

3. In a disk-sharpening tongs, a tong arm pivotally mounted and carrying a cutting blade at one end, and a second tong arm 40 pivotally mounted relative to the first arm and having a roller pivoted at one end in opposition to said blade, the pivot stud having an elongated head and the second arm having a corresponding slot arranged at 45 an angle to the trend of said head when the arms are in their normal operative positions, whereby the second arm may be readily removed and replaced by extending it to a particular angle relative to the first arm, 50 and is held against removal when in normal operative position.

ISAAC H. FARMER.
